UNITED STATES PATENT OFFICE.

COLONEL D. JENNINGS, OF PARK, VIRGINIA.

BIT.

1,118,777.

Specification of Letters Patent.

Patented Nov. 24, 1914.

Application filed February 18, 1913. Serial No. 749,189.

To all whom it may concern:

Be it known that I, COLONEL D. JENNINGS, a citizen of the United States, residing at Park, in the county of Grayson and State 5 of Virginia, have invented certain new and useful Improvements in Bits, of which the following is a specification.

This invention relates to improvements in wood working tools and particularly to bits 10 adapted especially for manual use.

The object in view is the production of a bit which is susceptible of application to an ordinary brace and especially designed for the production of corner blocks and rosettes.

15 A further object is the increasing of the facility for sharpening and maintaining sharpened a bit of the type specified.

The invention comprises certain novel constructions, combinations and arrangements of parts, as will be hereinafter specified and claimed.

In the accompanying drawing:—Figure 1 is a perspective view of a bit embodying the features of the present invention, the bit being shown as engaged by the chuck of an ordinary brace. Fig. 2 is a view in side elevation thereof, a fragment of a block operated upon by said bit being illustrated. Fig. 3 is an end view of the bit. Fig. 4 is an edge 30 view thereof.

Referring to the drawing by numerals, 1 indicates the shank of a bit which terminates in a centering or penetrating point 2, and the body portion of the shank is provided with a preferably integral, laterally extending web 3 whose lower edge is formed into a cutting surface by being beveled as indicated at 4, the beveled portion of such lower edge being formed with arcuate 40 notches 5, each produced by a concave recess 6 formed in the material of the web 3 and inclined correspondingly to the inclina-

tion of the beveled portion 4 so as to form a cutting edge about the lower terminus of each recess so that each notch 5 will have a 45 corresponding bead in the material operated upon by the bit. The material of the lower edge of the web is curved upwardly and outwardly, as indicated at 7 at the juncture with the centering point 2, and at the outer 50 or extreme free end portion of the lower edge of the web 3 said edge is curved downwardly forming a projection 8 which is adapted to produce an annular groove designed to be circumscribed about the main 55 portions of the rosette produced by the intermediate parts of the cutting edge of the web 3. The upper end portion of the shank 1 is preferably shaped to be engaged by any ordinary chuck 9, as for instance that of the 60 usual brace.

Having thus described the invention, what is claimed as new is:—

A bit comprising a shank having a centering point and an upwardly tapering web 65 outstanding laterally from the shank at one side only of the latter, the web being flat and formed with a cutting edge along its lower edge and the material of the lower edge of the web being curved downwardly 70 toward the portion of the shank terminating in the penetrating point, and a cutting projection depending from the outer terminus of the lower edge of the web, the cutting edge of the web being formed by a beveled 75 formation divided into cutting elements and located on the lower edge of the web.

In testimony whereof I affix my signature in presence of two witnesses.

COLONEL D. JENNINGS.
